UNITED STATES PATENT OFFICE.

JAMES J. COLLINS, OF SPRINGFIELD, MASSACHUSETTS.

NON-REFILLABLE BOTTLE.

No. 800,985.

Specification of Letters Patent.

Patented Oct. 3, 1905.

Application filed March 17, 1905. Serial No. 250,589.

To all whom it may concern:

Be it known that I, JAMES J. COLLINS, a citizen of the United States of America, and a resident of Springfield, in the county of Hampden and State of Massachusetts, have invented certain new and useful Improvements in Non-Refillable Bottles, of which the following is a full, clear, and exact description.

The object of this invention for improvements in non-refillable bottles is to provide devices of the class indicated which are of simple and durable construction, susceptible of inexpensive production, and efficient in the action to baffle attempts at refilling.

15 The invention consists in the combination and arrangement of parts and the constructions of certain of the parts, all substantially as hereinafter fully described, and set forth in the claim.

20 The improved device is fully and clearly illustrated in the accompanying drawings, in which--

Figure 1 is a central vertical longitudinal sectional view through the neck portion of a bottle, with the new device in place thereon. Fig. 2 is a horizontal cross-section on line 2 2, Fig. 1. Fig. 3 is a perspective view of the casing comprised as one of the components of the new device and which includes the valve-seat as a part thereof, a part of said casing being represented as broken away. Figs. 4 and 5 are perspective views of the guard included as a part of the new device and as seen in different positions. Fig. 6 is a perspective 35 view of the valve.

Similar characters of reference indicate corresponding parts in all of the views.

In the drawings, A represents a bottle having in the neck portion thereof near the junction of the neck with the body an internal annular groove *a*, which may be produced by molding in the original manufacture of the bottle.

B represents the cylindrical casing, which 45 may be made in the form of a thin shell having at the bottom thereof an annular wall *b* with the central valve-seat opening *d* therethrough, and said casing, moreover, has opposite downwardly-projecting prongs *f f*, provided with short outwardly-extending lugs or projections *g g*, all so that the said shell or casing, closely fitting the passage through the bottle-neck, may by the said prong projections *g g* be interlocked in the said groove *a*, 50 it being understood that in forcing the casing down to its place the said prongs, which are

of spring nature, will be forced slightly toward each other until the projections *g g* reach the groove, whereupon the prongs react outwardly, insuring the interlocking in such 60 a manner as to absolutely prevent the withdrawal of the casing without demolishing the bottle. C represents the guard device, the body *h* of which is of a cylindrical form and of somewhat less diameter than that of the cylindrical opening within the casing *b* and has upper and lower annular flanges *i i*, whereby there is produced an endwise-inclosed annular chamber between the inner wall of the casing and the outer surface of the body of the guard. 65 70

The guard-body has openings 10 and 12 leading from the upper and lower ends thereof to intersect transverse openings 13 13 at different levels and separated by an intermediate solid portion *h* of the body, so that 75 there is through the guard a devious passage-way efficient to prevent insertion through the guard of a wire or other object to reach the valve D, which is in space suitable therefor between the bottom of the guard and the 80 valve-seat portion of the casing. The guard has extending downwardly from its lower end and at one side thereof a lug *j*, to which the ear or ears *k* of the valve are pivoted at *m*.

The guard carrying the valve is combined 85 with the casing, having the valve-seat portion before the casing is forced into and interlocked with the internally-grooved bottle-neck. These parts B and C are permanently united 90 by a cross-pin *n*, which transversely intersects both the wall of the casing and the body of the guard.

As manifest, the inversion of the bottle results in the opening of the valve in an outward direction, permitting the liquid to flow 95 through the valve-seat opening into and through the bottom opening 12 and intersecting cross-openings 13 of the guard to the annular chamber between the guard and casing-wall, thence through the second series of 100 transverse passages 13, which intersect each other, and the passage 10 for free discharge at the mouth of the bottle.

The materials from which the new devices comprised in this non-refillable bottle may be 105 of such as have fitness to the purpose—as, for instance, the outer shell or casing may be made of metal or combinations of metal and other material, the lug-provided prongs *f f* being necessarily spring reactive—and the guard 110 may advantageously be of porcelain, glass, wood, aluminium, or other material, due regard

being had of course to the character of the contents for which the bottles are designed.

Having thus described my invention, what I claim, and desire to secure by Letters Patent, is—

In a non-refillable bottle in combination, the bottle-neck having in its neck portion an internal annular groove, a cylindrical casing having a valve-seat opening in its bottom and having downwardly-extending spring prongs with outwardly-turned lugs to interlock in said annular groove, a guard-piece having its body of cylindrical form and of less diameter than the passage through the casing, provided with external upper and lower flanges, closely fitting in the casing, having a depending lug and constructed with separated upper

and lower vertical passages, and with cross-passages at different heights, intersecting the vertical passages and communicating with the annular space between the guard-body and the internal wall of the casing and at points intermediate of said upper and lower flanges, means for connecting the said casing and guard, and a valve coöperating at said valve-seat opening and pivotally connected at one side thereof to the said depending lug of the guard.

Signed by me at Springfield, Massachusetts, in presence of two subscribing witnesses.

JAMES J. COLLINS.
